UNITED STATES PATENT OFFICE.

HARM FOLKERS, OF AUSTINVILLE, IOWA.

HAYRACK AND WAGON-BOX LIFTER.

Application filed May 3, 1923. Serial No. 636,290.

To all whom it may concern:

Be it known that I, HARM FOLKERS, a citizen of the United States, residing at Austinville, in the county of Butler and State of Iowa, have invented certain new and useful Improvements in Hayrack and Wagon-Box Lifters, of which the following is a specification.

In carrying out the present invention, it 10 is my purpose to provide a highly improved form of structure, whereby hay racks and wagon boxes may be removed from or applied to their respective supporting vehicles.

The primary object of the invention re- 15 sides in the provision of such a device that is extremely simple of construction, and efficient and positive in operation, the invention also embracing the desired features of durability and rigidity.

20 The nature and advantages of the invention will be better understood when the following detailed description is read in connection with the accompanying drawings, the invention residing in the construction, 25 combination, and arrangement of parts as claimed.

In the drawings forming part of this application, like numerals of reference indicate similar parts in the several views, and 30 wherein:

Figure 1 is an end elevation of my improved lifter.

Figure 2 is a cross section upon the line 2—2 of Figure 1.

35 Figure 3 is a perspective of one of the hoisting bars used in the invention, and

Figure 4 is an enlarged fragmentary cross section through a portion of the frame.

Referring to the drawings in detail, my 40 invention comprises a substantially square shaped open frame of suitable height, designated generally 5. This frame comprises vertical corner posts 6 and longitudinal and transverse connecting bars 7 and 8, respectively, these cross bars being braced with respect to the corner posts 6, through the medium of connecting rods 9.

Journalized between adjacent corner posts 6 beneath one of the transverse bars 8 is 50 a shaft 10, one end thereof being equipped with a bevelled gear 11 that meshes with a bevelled gear 12 upon a vertical shaft 13. As more clearly shown in Figure 1, this shaft 13 is supported in bearings 14 upon 55 the adjacent corner post 6, the lower end thereof being also equipped with a bevelled

gear 14' that is in mesh with a bevelled gear 15 upon a stub shaft 16. This stub shaft 16 is journaled within a bearing 17 formed upon one end of an arm 18, that 60 is secured to said post. The stub shaft 16 is provided with a crank handle 19, whereby the same may be rotated.

Connected at one end to the shaft 10 is a pair of cables 20, while also connected 65 at one end to the shaft 10 and outwardly of the said cables 20 are other cables 21, these last mentioned cables extending forwardly as shown in Figure 2 and engaged over pulleys 22 that are loose upon a stationary cross shaft 23. The lower ends of each of the cables 20 and 21 are equipped with hooks 24, Figure 3, that engage through openings 25 in the opposite ends of cross bars 26, these cross bars adapted to be 70 positioned beneath a hay rack or wagon box A.

In view of the above description, it will 75 at once be apparent that when the bars 26 are positioned beneath the hay rack or wagon box, the stub shaft 16 is rotated for consequently rotating the cross shaft 10 and winding the cables 20 and 21 thereon for effectively lifting the said hay rack or wagon box.

80 The advantage of a device of this character will be readily appreciated by those skilled in the art, and even though I have herein shown and described the most practical embodiment of the invention with 85 which I am at present familiar, it is nevertheless to be understood that minor changes may be made therein without departing from the spirit and scope of the invention 90 as claimed.

95 Having thus described my invention, what I claim as new, and desire to secure by Letters Patent, is:

A wagon box lifter comprising posts fixed 100 at points, said posts being arranged in pairs, the posts of each pair being spaced from each other, cross bars mounted upon the posts of each pair and bracing the same between the posts, other bars interposed between the pairs of posts and the first mentioned cross bars, a shaft connected at its ends with the last mentioned bars, pulley blocks mounted upon the said shaft and movable longitudinally thereof, a shaft journaled for rotation in the members of one of 105 the pairs of posts and bridging the space between the said posts, means mounted upon 110

one of the posts and adapted to be manually operated for rotating the last mentioned shaft, a set of cables connected with the last mentioned shaft and adapted to wind thereon and having end portions depending therefrom, a bar detachably connected with the free ends of the said cables and bridging the space between the said cables, other cables connected with the last

mentioned shaft and arranged to wind thereon, the last mentioned cables being trained through the pulley blocks and having end portions depending therefrom, and a cross bar detachably connected with the free ends of the last mentioned cables and bridging the space between them.

In testimony whereof I affix my signature.
HARM FOLKERS.
